S. MILANO.
SIGNAL MECHANISM.
APPLICATION FILED FEB. 11, 1915.

1,242,575.

Patented Oct. 9, 1917.

UNITED STATES PATENT OFFICE.

SILVESTRO MILANO, OF NEW YORK, N. Y.

SIGNAL MECHANISM.

1,242,575.

Specification of Letters Patent.

Patented Oct. 9, 1917.

Application filed February 11, 1915. Serial No. 7,509.

To all whom it may concern:

Be it known that I, SILVESTRO MILANO, a citizen of the United States, residing at the city of New York, county of Bronx, and State of New York, have invented a certain new and useful Signal Mechanism, of which the following is a specification.

This invention is a signal adapted to be operated automatically by the presence of gas in a room or apartment, or by smoke or fire therein, so as to awaken persons sleeping in said apartment, whereby asphyxiation of the sleeper or loss of life by fire is prevented.

15 It is well known that illuminating gas may at times escape from a cock or burner, due to carelessness in turning off the burner or from other causes, so that the gas will fill one or more apartments in which persons may be sleeping, resulting in gas poisoning or asphyxiation. Furthermore, it is not unusual for sleeping persons to become smothered by smoke or to be burned fatally by fire in an apartment.

25 My invention consists of a circuit maker and breaker embodying a thermostatic spring responsive to abnormal temperature changes for the purpose of controlling a signal, together with means sensitive to the presence of illuminating gas so that when subjected thereto said means will generate heat sufficient to influence the circuit maker and breaker for actuating the signal.

In the preferred form of the invention, 35 the circuit maker and breaker embodies a composite metal element in the form of a leaf or bow-shaped thermostatic spring forming a terminal of an electric circuit, the other terminal of which circuit is a contact in the path of the thermostatic spring. The circuit making and breaking spring is composed of metals having different degrees of expansion, such as iron or steel and zinc, the novelty in which thermostatic spring resides in the union of the two metals secured by punching holes therein so as to displace the softer metal (zinc) into the holes of the iron or steel strip, thereby uniting the metals in intimate contact with each other and owing to the low fusing point of the zinc the spring is rendered sensitive to the action of heat.

It is well known that certain substances, such as spongy platinum, when exposed to combustible gases will become heated to a glowing condition. I utilize this property

of the substance in the production of an element which is positioned in close proximity to the thermostatic spring, and should illuminating gas escape into the room or compartment and flow into contact with the aforesaid element, the latter will become heated to a glowing condition, whereby the heat generated by said element will influence said composite thermostatic spring so as to control the signal, the latter being either audible or visual.

Other features of the invention and the advantages thereof will appear in the course of the following detailed description.

In the drawings,

Figure 1 is a plan view illustrating my device in connection with a suitable signal circuit, the latter being indicated diagrammatically.

Fig. 2 is a cross section on the line 2—2 of Fig. 1.

Fig. 3 is a detail perspective view of the thermostatic composite spring removed from the supporting device or casing.

Fig. 4 is a cross section through the thermostatic spring.

Fig. 5 is a plan view of one form of heat-generating device embodying spongy platinum, the same being partly broken away and in section, and being illustrated in operative relation to the thermostatic composite spring, the latter being in dotted lines.

Fig. 6 is a cross section through the heat-generating device of Fig. 5.

A designates the thermostatic element and B a heat-generating device positioned in proximity to said thermostatic element, the whole being supported on a base C.

The thermostatic element is shown in Figs. 1, 2, 3 and 4 in the form of a composite metal spring, the same comprising two layers of metal *a a'*, one metal being softer than the other, and one metal being a spring. The spring metal consists of iron or steel, whereas the softer metal consists of zinc, the two layers of metal being in intimate contact and united firmly together so that the spring will be influenced by an increase in the temperature above the normal. As shown, the spring is perforated, the openings *d* being provided at intervals in the length of said spring. It is apparent that the two metal pieces composing the spring may be united in a suitable manner, but for economy of manufacture it is preferred to stamp or "blank out" the pieces

a a' and to unite them together by punching apertures at *d* in such manner that the softer metal is displaced during the punching operation, so that the softer metal will enter the apertures in the spring metal, as indicated at *d'* in Fig. 4, whereby the displaced parts of the soft metal entering the apertures of the spring metal operates to unite or combine the two metals into intimate contact along their meeting faces.

The spring is shown in Fig. 3 as having an enlarged end portion *e* provided with apertures *e'*, whereby the spring may be rigidly fixed to the supporting member. The spring is shown in Fig. 1 as forming one terminal of an electric circuit *D*, the latter including a suitable source of electric energy, such as the battery *f*, and a signal device of suitable character, such as the bell *E*, but it is apparent that I may use a visual signal as a substitute for the audible signal. The conductors of the electric circuit are attached to binding posts *g* fixed in a suitable way on the supporting or base member *C*, and from one of these binding posts extends a conductor *g'* secured in electrical contact with the enlarged end portion *e* of the thermostatic spring. From the other binding post extends a conductor *g''* which is electrically connected with the base *h* of a contact *h'*, the latter being in the path of the free end of the spring *A*. Normally the spring is free from contact with the screw *h'*, thus interrupting the electric circuit, but when the thermostatic member is influenced by heat the free end of said member makes mechanical and electrical contact with the screw *h'*, thus closing the electric circuit and operating the signal device.

An important feature of my invention is the heat generating device *B*, two forms of which are shown. In the embodiment shown in Figs. 1 and 2 the heat generating device consists of a supporting wire *i*, a series of insulating sleeves *i'* threaded on the wire, and pieces of spongy platinum *I* attached to the insulating sleeves, said pieces of spongy platinum being separated from each other by the sleeves. The wire of the heat generating device is supported in fixed posts *j* attached to the base *C*. Said heat generating device is positioned in proximity to the thermostatic spring *A* and, as shown in Fig. 1, an end portion of the heat generating device is bent or curved to correspond with the curvature of the attached part of the spring, whereby the spongy platinum material of device *B* is quite close to the spring along the straight and curved parts thereof.

In Figs. 5 and 6 of the drawings there is shown another embodiment of the heat generating device consisting of a plurality of wires *k* and a mass of spongy platinum

k', said wires being embedded in the spongy platinum mass for the latter to incase the wires for substantially the length thereof. The end portions of the wires are extended beyond the platinum mass in order that the device may be supported in the posts *k''*, and, if desired, the end portion of said device may be bent or curved the same as in Fig. 1, in order that the spongy platinum material may be positioned quite close to the curved end of the spring, the latter being indicated in dotted lines.

The supporting device *C* is shown as a casting open on one side, but it is apparent that the particular form of device may be modified or varied as desired.

The operation of the invention will be apparent from the foregoing description taken in connection with the drawings. The signal device may, of course, be positioned in the same room or apartment as the thermostatic device, or said signal device may be in a remote room or apartment from the signal device so as to be connected therewith by the conductors of the electric circuit. Should a fire occur in the room wherein the thermostatic device is located, the heat of the fire will influence the thermostatic spring, the different metals of which respond to the different degrees of heat. The spring is thus deflected from the normal position shown for the free end of the spring to contact with screw *h'*, thereby closing the circuit and operating the signal. Should illuminating gas escape from a cock or burner and flow into contact with the spongy platinum material *I*, the latter will generate heat until the spongy platinum material is in a glowing condition, and the heat from this material *I* will influence the thermostatic spring *A* for closing the circuit, thus again operating the signal under conditions different from the condition first described.

My device is operated either by the heat from a fire or by the flow of illuminating gas into contact with the spongy platinum material and the invention is thus adapted to operate a signal which will minimize the danger of loss of life due either to the presence of a fire or to the escape of illuminating gas.

Having thus fully described the invention, what I claim as new, and desire to secure by Letters Patent is:

1. In a thermostatic and gas detecting signal device, the combination with a circuit terminal, of a composite thermostatic member positioned for electrical contact with said circuit terminal, said composite thermostatic member being responsive to temperature changes in the surrounding air and operating through the circuit terminal to control a signal, and a heat-generating element separate from said thermostatic mem-

- ber, said heat-generating element being positioned in such proximity to the thermostatic member as to operate directly thereon and to influence the same for controlling 5 the signal, said heat-generating element being composed of material responsive to the action of gas containing hydrocarbon, whereby the contact of such gas with said element generates heat the effect of which 10 upon the thermostatic member is to control the signal independently of any change in the temperature of the air to which said thermostatic member is normally responsive.
2. In a thermostatic and gas detecting 15 signal device, the combination with a circuit terminal, of a composite thermostatic spring positioned for electrical contact with the circuit terminal, said thermostatic spring being responsive to a change in temperature 20 of the surrounding air and said spring operating through said circuit terminal to control a signal, a heat-generating element separate from the thermostatic spring, and means for fixedly supporting the heat-generating 25 element in close proximity to said thermostatic spring, said heat-generating element being composed of a material sensitive to the action of gas containing hydrocarbon and adapted, when such gas flows 30 into contact therewith, to generate heat which directly influences the thermostatic spring so as to change the position of said spring and to control said signal independently of a change in temperature of the surrounding 35 air to which temperature change the thermostatic spring is normally responsive.
3. In a thermostatic and gas detecting signal device, the combination of a composite 40 thermostatic spring for controlling a signal by a change above a predetermined limit in the temperature of the air surrounding said thermostatic spring, said spring being bowed at one end portion and said bowed portion being fixedly attached, a circuit ter-
